(57) **CLAIM**

The ornamental design for a gun buttstock holder, as shown and described.

DESCRIPTION

FIG. 1 is a front and bottom view of a gun buttstock holder, showing my new design;

FIG. 2 is a front elevation view thereof;

FIG. 3 is a rear elevation view thereof;

FIG. 4 is a left side elevation view thereof;

FIG. 5 is a right side elevation view thereof;

FIG. 6 is a top plan view thereof;

FIG. 7 is a bottom plan view thereof; and,

FIG. 8 is an enlarged view of detail “8” identified in FIG. 2. The dashed lines in the figures illustrate portions of the gun buttstock holder that form no part of the claimed design. The dash dot dash lines in the figures depict the claim boundary and form no part of the claimed design. The subject matter inside of the claim boundary is claimed. The subject matter outside of the claim boundary forms no part of the claimed design.

The dash dot dot dash lines in FIGS. 2 and 8 are for the purpose of illustrating the enlarged view indicators and form no part of the claimed design.
